UNITED STATES PATENT OFFICE.

ZACCUR PRALL BOYER, OF PHILADELPHIA, PENNSYLVANIA.

CABLE-RAILWAY CONSTRUCTION.

SPECIFICATION forming part of Letters Patent No. 365,964, dated July 5, 1887.

Application filed March 12, 1887. Serial No. 230,705. (No model.)

To all whom it may concern:

Be it known that I, ZACCUR PRALL BOYER, a citizen of the United States, residing at Philadelphia, in the county of Philadelphia and 5 State of Pennsylvania, have invented certain new and useful Improvements in Cable-Railway Construction; and I do hereby declare the following to be a full, clear, and exact description of the invention, such as will enable 10 others skilled in the art to which it appertains to make and use the same.

My invention relates to improvements in cable-railway construction, and refers more particularly to my Patent No. 354,531, patented December 21, 1886; and it consists in 15 various features of construction and arrangement, which I will proceed to describe, and point out in the claims.

It has been found by experience in the construction of cable railways that it is sometimes necessary for two or more different railways to use the same street or streets, and it has also been developed that it is desirable by each railway company, where different roads 25 occupy the same street, that each railroad use its own propelling-cable. It has also been developed that where railroads already occupy streets which are desired to be used by other railroads it has been found impossible to construct entirely different systems on same street, owing to the streets being narrow, and in 30 some cities the law regarding railroads limiting the space as regards railroad-tracks. To this end I have devised the following construction of cable-railway systems.

Heretofore it has been that where separate railway companies occupied the same street they use different conduits and cables, or that one railway company uses the cable and conduit of the other company where it is desired to use so much of their road as may come on their line of route.

By my invention two different roads may use the same conduit, each with its own traction-cable, and with an arrangement of track system which will take up but a minimum additional track space.

In the drawings, Figure 1 represents a diagrammatic plan view showing the arrangement of tracks where two different railroads

occupy the same street, a double track system being shown. Fig. 2 is a perspective sectional elevation showing my improved conduit with track arrangement.

In the drawings, A represents the conduit, 55 which is formed substantially as shown in my patent above referred to, except it is made wider and the yoke-arms a little longer.

B are the bracket-blocks, C the braces, D the sheet-metal casing, all of which are shown 60 and described in my patent before mentioned.

F is a central partition, which divides the conduit into two compartments, F' F''. This partition is made of steel and formed with the channel portion F''. This division-plate 65 is securely fixed to the bottom of the conduit in any suitable manner, and is also braced by the horizontal plates G, which plates may be the journal-bearings for the cable-carrying rollers. The inclined upwardly-extending 70 side flanges, f, of the channel-bar form each one of the slot-rails, the other slot-rail, H, being as shown in my former patent referred to. The track-rails I I are seated in chairs J J', and are securely bolted to same by brace-rods 75 K K', as shown. The conduit, it will be observed, is embedded in a concrete base, and the part between the rails also concreted, and the pocket X of the channel-bar is also filled with concrete, which allows a perfectly smooth 80 surface and prevents any undue jarring or disarrangement of the conduit and slot-rails.

By referring to Fig 1, we will assume there are two different railways and explain their relation to each other. For convenience of 85 reference, I will term one the W. & G. Road and the other Traction Road. L 15 represents the streets upon which W. & G. road runs. 17 L M represent the streets upon which the Traction road runs. It will be seen that the 90 Traction road runs into L street at 17 and leaves L at M. The W. & G. road runs from L to 15, as shown. It will thus be seen that the two roads occupy L street from 17 to 15. On this street the tracks of one road are arranged parallel, with about eight inches space between the rails. Between each set of track-rails are arranged the slots S S'. At the junction of the two roads the wide double conduit is used until the roads diverge, when 95 100

each takes its own single conduit again, the arrangement of such conduits being well understood by those skilled in the art.

It will thus be seen that by this arrangement several roads may run on one street in approximately the same space, and yet use different track-rails and different propulsion-cables.

While I have shown my invention applied to a conduit, as shown in my previous patent, it may be readily adapted to any other style of conduit.

I claim—

1. In a cable traction railroad, the combination, with the cable-conduit, of a vertical division-plate suitably secured therein and forming two separate compartments, substantially as shown.

2. In a cable traction railroad, the combination, with the cable-conduit, of a vertical division-plate, which is suitably secured therein, and whose top part is arranged intermediate of the outer slot-irons of a double-track system, substantially as shown.

25 3. The combination, with the yoke of a cable-conduit, of a division-plate secured thereto,

said yoke and division-plate having slot-irons secured thereto, substantially as shown.

4. In cable-conduits, the division-plate adapted to be secured to the bottom of the conduit and provided with the channel portion, the side thereof forming slot-irons, substantially as shown.

5. In combination with the yoke of a cable-conduit, a division-plate secured thereto and the lateral braces G, substantially as shown.

6. In cable railways, a conduit composed of yokes formed from a single bar or rail, said yokes having the central partition-plates secured thereto, the lateral-extending arms of 40 said yokes having the chairs secured thereto, adapted to receive the track-rails, the angle-blocks, the slot-rails, and the metal casing, all constructed and arranged substantially as shown and described.

In testimony whereof I affix my signature in presence of two witnesses.

ZACCUR PRALL BOYER.
